UNITED STATES PATENT OFFICE.

JOHN W. LIND, OF BOSTON, MASSACHUSETTS, ASSIGNOR OF ONE-HALF TO
JOHN J. MORRIS, OF SAME PLACE.

PIPE-WRENCH.

SPECIFICATION forming part of Letters Patent No. 602,340, dated April 12, 1898.

Application filed May 21, 1897. Serial No. 637,570. (No model.)

To all whom it may concern:

Be it known that I, JOHN W. LIND, of Boston, (Roxbury,) in the county of Suffolk and State of Massachusetts, have invented certain new and useful Improvements in Pipe-Wrenches; and I do hereby declare the following to be a full, clear, and exact description of the invention, such as will enable others skilled in the art to which it appertains to make and use the same.

This invention relates to pipe-wrenches, and has for its object the production of a wrench in which shall be combined the advantages of adjustment for use upon different sizes of work presented by the monkey-wrench type, with the security of grip and flexibility of operation as a pipe-wrench presented by the so-called "plier" or "tong" type. To this end the jaws are furnished with shanks or handles extended away from their respective jaws in proximity to each other and capable of both a lengthwise and an angular movement in adjustment relatively to each other, means being provided to enable the wrench members to be fixed in adjusted longitudinal position, while permitting an angular variation sufficient to allow the wrench to be turned about a pipe or the like to get a fresh grip.

The various features of my invention will be fully illustrated and described in the accompanying drawings and specification and set forth in the claims.

In the drawings, Figure 1 is a view in side elevation of a wrench in the construction of which my invention has been embodied. Fig. 2 is a front elevation of the same, and Fig. 3 a view in side elevation of a movable member of the form illustrated in Fig. 1 separate from the wrench.

In the preferred embodiment of my invention selected for illustration and description the jaws 1 and 4 are suitably connected for manipulation by and in the instance illustrated are shown as formed integral with their respective shanks 2 5, the jaw 1 and shank 2 constituting what may be designated for the sake of convenience as the "stationary" member of the wrench, while reference

will be made to the similar part 4 5 by the term "movable" member.

As indicated, the members are assembled with the jaws presented in opposed relation, their neighboring faces being suitably curved and serrated, preferably as illustrated, to secure a good grip, while in the position illustrated the shanks lie extended in substantial parallelism, affording a compact handle.

Any suitable means may be utilized to prevent lateral displacement of the members relative to each other, and as one form of construction to serve this end I have shown one member, in this instance the stationary member, as slotted from front to rear throughout a considerable portion of its length to receive the movable jaw, which is free at times to change its position lengthwise of the slot for adjustment to pieces of work differing considerably in size. Provision is also made for variation of the movable member with relation to the other member by forming the same of suitable contour, and preferably the contour will be such as to permit the shanks of the movable and stationary members to overlap throughout the greater part of their length, in this instance the shank 5 being permitted to retire into the slot.

The means to fix the members in fixed longitudinal relation while permitting angular variation may take any convenient form, and as one such arrangement I have illustrated an auxiliary controlling member 6 intermediate the members and to connect them at times. Such connection may be effected suitably by roughening or serrating the shank 2, as at 3, and bringing into engagement with this the intermediate portion of the controlling member or rod 6, which is of suitable shape therefor, a projection 7 serving this purpose in the instance illustrated, the rod 90 being arranged at its forward end to connect with the jaw 4 and receive the thrust thereon during operation of the wrench. For the purpose of this connection in the form shown the jaw 4 at its lower edge, adjacent the shank 95 of the stationary member, enters a slot in the end of the rod 6 and is pinned in place therein. This pin serves, further, to limit the move

ment of the movable member rearwardly in the slot of the stationary member, while on the other side of the stationary member a thickening projection or pin 8 on the movable member limits the forward movement of the jaw 4, these limiting means being positioned suitably to allow change in the angular relation of the members.

In operation the auxiliary member 6 can be controlled by one or two fingers of the hand in which the shanks are held, the jaws adjusted in longitudinal position to the pipe or other work, and there fixed by surrounding the controlling member with the fingers and grasping it together with the shanks. After giving a turn to the pipe if the fingers be relaxed the jaws upon turning of the wrench will separate slightly by reason of slight change in the angular relation of the members and will slip on the pipe, a renewed grasp of the members causing fresh engagement of the work by the jaws for the next turn.

Having thus fully described my invention, I wish it understood that I do not limit myself to the exact construction and arrangement of parts illustrated, since the same may be varied considerably without departing from the spirit of my invention.

Having thus described my invention, what I claim as new, and desire to secure by Letters Patent, is—

1. In a pipe-wrench, the combination of a stationary jaw having its shank slotted, a movable jaw positioned within the slotted shank of the stationary jaw, and capable of longitudinal and angular adjustment with relation thereto, the shank of the stationary jaw being provided with a series of teeth, a rod secured at one end to the movable jaw, a lug formed on said rod adapted to engage the teeth of the stationary jaw when its lower end is contracted, and means for preventing

the movable jaw from becoming disengaged from the slot of the stationary jaw, substantially as set forth.

2. The combination of a stationary jaw, having its shank slotted longitudinally, a movable jaw adapted to move within said slot, a pin extending through the stationary jaw on the outer side of the shank of the stationary jaw, a rod secured to the movable jaw on the opposite side of the shank of the stationary jaw, whereby said jaw is prevented from becoming displaced from the slot in which it moves, a series of teeth formed on the shank of the stationary jaw, and a lug carried by the rod for engaging said teeth when the opposite end of the rod is contracted, substantially as set forth.

3. In a pipe-wrench, a plurality of members each comprising a pipe-gripping jaw, and a shank connected rigidly to and to manipulate said jaw, said shanks being extended in proximity to each other, and means, extended along said shanks, to fix said members in adjusted longitudinal position relative to each other, while permitting variation in their relative angular position, substantially as described.

4. In a wrench, a plurality of loosely-assembled members each comprising a jaw and a manipulating-shank; means to prevent displacement of said members; and an auxiliary controlling member extended in proximity to said manipulating-shanks, to fix said members in adjusted longitudinal position, while permitting variation in their angular relation, substantially as described.

In testimony whereof I have signed this specification in the presence of two subscribing witnesses.

JOHN W. LIND.
